BURNER

Henry J. Keeley, Denver, Colo.

Application September 30, 1933, Serial No. 691,649

8 Claims. (Cl. 110—40)

This invention relates to a burner for solid, granular fuels, such as fine steam coal. The principal object of the invention is to provide a burner which can be employed to efficiently burn the cheaper grades of coal and extract a high percentage of heat units therefrom.

Another object of the invention is to provide a burner in which the combustion gases will be thoroughly and intimately admixed with heated combustion air before reaching the flame area.

Further objects are to provide a continuous type burner in which fresh fuel will be constantly fed into the gasifying area; in which a violent spiral or whirling action will be imparted to the air and combustion gases to intimately admix them; and which is adaptable for placement in the fire boxes of any of the conventional types of heating plants, boilers, etc.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a plan view of a typical burner embodying the present invention. In this view, portions of the burner have been broken away to illustrate the interior construction.

Fig. 2 is a vertical section therethrough, taken on the line 2—2, Fig. 1.

Fig. 3 is a fragmentary detail perspective view illustrating the type of grate bar employed in the invention.

Fig. 4 is a detail view illustrating the action of the grate bars.

Fig. 5 is a detail enlarged section through the grate and air conduits taken on the line 5—5, Fig. 2.

Construction

The invention comprises a suitable supporting frame 10 upon which is carried a bowl 11 of suitable refractory fire resisting material. The bowl 11 is preferably formed of a porous material such as porous fire clay, carborundum, aluminum oxide, or the like. To assist the porosity thereof, it may be provided with a plurality of perforations 12 extending through its walls. The bottom of the bowl 11 is provided with a rectangular fuel opening 13 and the top with a discharge

opening 14. The discharge opening 14 is covered by means of a refractory plate 15 supported thereover upon fire resisting pedestals 16. A series of traveling grate bars 17 passes immediately below the fuel opening 13 over suitable supporting sprocket wheels 18.

A pair of air conduits 19 and 20 is positioned below the upper reach of the grate bars 17. The air conduit 19 is fed from an air supply line 21 positioned on one side of the burner. The conduit 20 is fed from a similar air supply 22 positioned on the other side of the burner. The conduits 19 and 20 discharge through special orifices which will be later described. The supply line 21 is provided with a branch line 23 extending upwardly on the right side of the bowl 11. The air supply 22 is provided with a similar branch conduit 24 extending upwardly on the left side of the bowl 11. The branch conduits 23 and 24 terminate in fire resisting nozzles 25 which extend through the wall of the bowl 11 on opposite sides, in opposed directions and at a series of different elevations in the bowl 11.

A spring actuated damper 26 is positioned in each supply line so as to automatically control the amount of air passing into the branch lines 23 and 24, and the pressure in the conduits 19 and 20. The dampers 26 are preferably provided with outwardly extending handles 27 connected with springs 28 which constantly urge the dampers 26 toward the closed position across the branch lines 23 and 24. The tension of the springs 28 can be adjusted by a suitable adjusting nut 29.

Fuel is fed to the traveling grate bars 17 by means of a continuous conveyor 30 terminating over the forward extremity of the grate bar series. The fuel is constantly fed to the conveyor 30 from any suitable hopper through a feed chute 31. The ashes are removed from the fire box by means of a suitable ash conveyor 43.

It is desired to call particular attention to the construction of the grate bars 17 which are illustrated more in detail in Figs. 3, 4, and 5. These bars are preferably cast integrally with a longitudinal beam 32 extending from end to end of the bar for supporting a series of spaced apart, T-shaped members 34 having inclined corrugated fuel-supporting surfaces 33. Below each surface 33 the sides of the T-shaped members are curved inwardly toward each other terminating in a relatively narrow bottom edge. A series of wedge-shaped members projects from one side of the beam 32 between each set of surfaces 33. These members will be herein designated as the upper

deflector prongs 35. A series of wider, flat-topped projections project from the beam 32 at a lower elevation and opposite to the upper deflector prongs 35. These will be herein designated as 5 the lower deflector prongs 36. The beam 32 terminates in end members carrying lugs 38, preferably provided with elongated heads as illustrated.

The series of grate bars are connected together 10 by means of suitable elongated links 39 which are passed over the elongated heads of the lugs 38 and thence turned sideways so as to be locked in place thereon as shown in Fig. 4. The end members are also provided with openings 15 40 for receiving the teeth of the sprocket wheels 18. The openings 40, however, may if desired be simply sockets at the bottoms of the end members. It is preferable, however, to have them pass completely through the members so that 20 they will clean themselves of ashes, coal, etc. When assembled on the series of links 39, the upper deflector prongs 35 pass into the adjacent bar between the faces 33 thereof and rest upon the lower deflector prongs 36 of the said adjacent 25 bar.

The upper walls of the air conduits 19 and 30 20 are formed with a series of laterally extending orifices 41. The orifices 41 on one of the conduits, for instance 19, extend upwardly adjacent the right side of the T-shaped members 34, as shown in Fig. 5. The orifices of the adjoining conduit, for instance 20, extend upwardly adjacent the left side of the T-shaped members 34, as shown in Fig. 5.

Operation

The air supply lines 21 and 22 are supplied 40 with air from any suitable source, preferably pre-heated through any suitable preheater so that it will enter the conduits at a relatively high 45 temperature. Coal is continuously fed to the grate bars 17 by the conveyor 30. As the coal passes across the fire opening 13 it will burn with sufficient intensity to release combustible 50 gases into the interior of the bowl 11. During the forepart of its travel across the fire opening, the air from the orifices 41 of the conduit 20 will pass upwardly against the curvated surface on the left of the T-shaped sections 34 which 55 will deflect it to the left over the deflector 35 at an angle. As the burning coal passes over the conduit 19, the orifices 41 therein will project air against the right curvated surface of the T-shaped sections 34, as shown by the arrows in Fig. 5.

Therefore, the gases arising at the fore part 60 of the bowl 13 are thrown to the left and the gases arising at the rear part of the bowl are thrown to the right. This imparts a spiral, whirling action to the gases in the bowl 11 which forces them into close contact with the heated bowl wall and intimately mixes the hot gases with the incoming air to form a perfectly combustible mixture. The whirling action of the gases is assisted by the heated air entering tangentially through the nozzles 25.

The intimately mixed, combustible gases percolate through the porous material of the bowl 70 and through the perforations 12 to the exterior thereof. The bowl is therefore entirely surrounded by a zone of hot combustible gas which is constantly oxidizing or burning to produce an incandescent, gaseous envelope entirely around 75 the bowl. Excess gases, which do not pass

through the bowl, exit under the cap 15 as an incandescent gaseous mixture.

It is desired to call attention to the fact that with this device all long flames are eliminated. The gases are intimately mixed at a high temperature so that they burn instantly with practically no flames to create an incandescent gaseous envelope for the bowl. The carburetion zone of the gases is relatively long and effectively agitated at a relatively high temperature 10 so that no carbonaceous material can escape oxidation and practically perfect combustion is obtained from the fuel. Very little ash is left upon the grate bars as they descend over the rear-most sprockets. Should any clinkers or other 15 fusible material form upon the grate bars, it will be broken loose therefrom by the rising and breaking action of the upper deflector members 35 as they pass over the sprockets 18. As illustrated in Fig. 2, a suitable wire brush 44 may be 20 provided to scrape and clean the grate bars before they re-enter the combustion zone.

The burner may be installed in any suitable heating plant. The position of the walls of a typical boiler fire box is indicated in broken line 25 at 45. It will be noted that the incoming fuel travels a relatively long distance within the highly heated fire box so that all moisture is eliminated and it is practically at the gasifying point at the time of deposit upon the grate bars. 30

It will be noted that a longitudinal groove 46 is formed along each side of each lower prong 36. These grooves are for the purpose of catching and holding fuel particles until they have been consumed so as to prevent them from passing 35 through the grate.

It is desired to call particular attention to the fact that the incoming air from the conduits 19 and 20 and from the nozzles 25, together with the combustion gases from the grate, are contained or enclosed within the limited space of the bowl 12. This results in a compression thereof which causes them to ignite with a compressive or explosive-like effect. This high compression of the confined gases causes both flammable gas and air to be forced through the porous wall of the bowl to cause a surrounding area of surface combustion about the bowl. 45

Attention is directed to the manner in which the fuel gases are distilled under the hood and 50 trapped until thoroughly mixed with the proper amount of oxygen for complete combustion thereby affording ample opportunity for the generation of radiant heat by surface combustion and otherwise without the customary flame pressure. 55

While a specific form of the improvement has been described and illustrated herein, it is desired to be understood that the same may be varied, within the scope of the appended claims, without departing from the spirit of the invention. 60

Having thus described the invention, what is claimed and desired secured by Letters Patent is:—

1. A fuel burner comprising: a series of traveling grate bars, said bars each consisting of a beam extending transversely of the line of travel; a series of spaced apart members having fuel supporting surfaces extending laterally of said beam; upper deflector prongs projecting from one side of said beam between and below said surfaces and extending beneath and between the corresponding fuel supporting surfaces on the next adjacent grate bar; and lower deflector prongs extending from the opposite side of said beam directly opposite said first prongs and be- 75

neath the upper prongs of the adjacent bar, said members being T-shaped in cross section with the stem portions coacting with said prongs and having their sides curved upwardly to direct air 5 passing between the upper prongs and said sides obliquely through the spaces between said fuel supporting surfaces.

2. In a fuel burner having a combustion bowl, means for imparting a whirling action to the 10 gases in said bowl comprising: a travelling grate positioned below said bowl, there being a first series of inclined passages through said grate for directing air in one direction; and a second series of oppositely inclined passages through said grate 15 for directing air in a different direction the paths of travel of the passages of the first series being out of alignment with the paths of travel of the passages of the second series; a first series of air nozzles below said grate at one side of said bowl, 20 adjacent the path of and communicating with the first series of passages; and a second series of air nozzles below said grate at the other side of said bowl, adjacent the path of and communicating with the second series of passages, so that 25 the air passing through said grate at one side of said bowl will be inclined in one direction and at the opposite side of said bowl will be inclined at an opposite direction so as to create a whirling effect in said bowl.

3. In a fuel burner having a combustion bowl, means for imparting a whirling action to the 30 gases in said bowl comprising: a travelling grate positioned below said bowl, there being a first series of inclined passages through said grate for directing air in one direction; and a second series of oppositely inclined passages through said grate 35 for directing air in a different direction, the paths of travel of the passages of the first series being out of alignment with the paths of travel of the 40 passages of the second series; a first series of air nozzles below said grate at one side of said bowl, adjacent the path of and communicating with the first series of passages; and a second series of air nozzles below said grate at the other 45 side of said bowl, adjacent the path of and communicating with the second series of passages, so that the air passing through said grate at one side of said bowl will be inclined in one direction and at the opposite side of said bowl will be inclined 50 at an opposite direction so as to create a whirling effect in said bowl; and means for projecting air tangentially through the side of said bowl in the direction of the air whirl caused by said grates.

4. A fuel burner comprising: a longitudinally traveling grate; an open bottomed fire pot positioned above said grate; a first series of longitudinally extending passages through said grate, said first series of passages being inclined upwardly toward one side of said grate; a second series of longitudinal passages through said grate, the 55 passages of said second series laterally alternating with the passages of said first series and being inclined toward the opposite side of said 60 grate; a first series of longitudinally extending air supply slots beneath the front portion of said

grate parallel with and directed into said first series of passages only; a second series of air supply slots beneath the rear portion of said grate parallel with and directed into said second series of passages only so that the air at the front and rear portions will be projected through said grate at angles to one another. 5

5. An endless travelling grate consisting of a series of grate bars lying in parallel relation across said grate, each of said bars comprising: 10 a main supporting beam linked at its extremities to the beams of its two adjacent bars and having a series of spaced apart members having fuel supporting surfaces secured to and extending laterally across the top of said beam; upper deflecting prongs projecting from one side of said beam between and below said fuel supporting surfaces; a lower deflector prong projecting from the other side of said beam opposite each upper deflecting prong; said upper deflector prongs projecting laterally beyond the fuel supporting surfaces of said members, and overlying the lower deflector prongs of the next adjacent beam. 15

6. A fuel burner comprising: a series of travelling grate bars, said bars each consisting of a 20 beam extending transversely of the line of travel and having a series of spaced-apart, transversely extending, T-shaped fuel supporting members extending across said beam with prongs projecting from said beam between and below the top of 25 adjacent fuel supporting members so as to coact with the latter to form oppositely inclined passages at the sides of each prong; a first series of air orifices below one portion of said grate bars directing air upward on one side of said prongs; 30 and a second series of air orifices below another portion of said grate directing air upwardly on the other side of said prongs.

7. A fuel burner including a combustion bowl and a traveling grate underlying said bowl and 35 having groups of air passages extending therethrough and arranged in rows, the adjacent passages in each row being oppositely inclined; a first series of air nozzles underlying one portion 40 of said grate and cooperating with the overlying 45 passages of like inclination; and a second series of air nozzles underlying a different portion of said grate and cooperating with the overlying 50 passages of opposite inclination.

8. A fuel burner including a combustion bowl and a traveling grate underlying said bowl and having groups of air passages extending therethrough and arranged in rows, the adjacent 55 passages in each row being oppositely inclined; a first series of air nozzles underlying one portion of said grate and cooperating with the overlying 60 passages of like inclination; a second series of air nozzles underlying a different portion of said grate and cooperating with the overlying 65 passages of opposite inclination, the said first portion of said grate being positioned beneath one side of said bowl; and the said second different portion of said grate being positioned beneath the opposite side of said bowl so as to impart a whirling action to the gases within said bowl.

HENRY J. KEELEY.
